UNITED STATES PATENT OFFICE.

JOHN B. OLSON AND JOHN G. SHODRON OF FORT ATKINSON, WISCONSIN, ASSIGNEES
TO JAMES MANUFACTURING COMPANY, OF FORT ATKINSON, WISCONSIN.

VALVED VENTILATOR INLET.

Application filed June 28, 1926. Serial No. 119,173.

This invention relates to valved ventilator inlets particularly adapted for use in so-called gravity ventilating systems such as are used in barns, stables, poultry coops, etc.

5 The primary object of this invention is to provide simple, inexpensive and practical means for controlling the admission of air to a building through a specially designed passage, the walls of which are designed to conform to the standard spacing and dimensions of floor joists,—the controlling devices being adjustable in accordance with weather conditions, and adapted to prevent reversals in the direction of the air 10 current such as occur under abnormal conditions of weather and wind.

In the drawings:

Figure 1 is a rear elevation of the improved inlet structure, showing the same in 15 position between the floor joists of a building.

Figure 2 is a view of the same in longitudinal section taken on line 2—2 of Figure 1.

Figure 3 is a detail view of one of the 20 intermediate bracket bearings, showing fragments of the supporting cross rods and the intake valve.

Like parts are identified by the same reference characters throughout the several 25 views.

An open ended rectangular casing 10 is adapted to fit between two floor joists A and A', which are spaced in accordance with the standard practice of spacing such joists 30 on 16 inch centers. The casing is supported in substantial contact with the floor B by suitable cleats 11 nailed to the joists near their lower margins after the casing has been adjusted in position.

40 Within the casing a sheet metal damper valve 12 has its lower portion pivotally mounted to swing about the axis of a supporting cross rod 13, the ends of which are near to the side wall of the casing. The 45 lower margin of the valve is provided with a weight 14 whereby the valve is substantially balanced upon the pivot rod 13. The portion of the valve 12 above the pivot rod 13 is adapted to seat in closed position 50 against a heat insulating lining having side portions 15 provided with obliquely disposed inner margins 16. Its top portion 17 has a bevelled margin at 18 which is inclined in correspondence with the oblique margins 16 55 of the side portions.

The sheet metal of the valve 12 is slotted at intervals along the line of the rod 13, and the material between the slits is pressed in opposite directions to form semi-cylindrical grooves 19 for the reception of the 60 pivot rod 13. An inclined sheet metal wall 20 is located in the rear of the portion of the valve below the pivot rod 13, and when the valve is closed the weight 14 impinges against the lower margins of this 65 wall. The wall 20 may comprise an upturned portion of the upper member of the double bottom wall 21.

The sheet metal wall 20 extends upwardly and rearwardly and has its upper margin 70 downwardly and rearwardly inclined in the form of a flange 23 which re-enforces and stiffens this wall. Brackets 25 having reversely bent end portions 26 and 27 secured to the wall 20 near the re-enforcing flange 23. Each bracket arm 26 projects through a slot in the wall 20 and is apertured to receive and support the rod 13. The other arm 27 of each bracket is similarly apertured, and these arms receive and support 75 a rod 28 from which an adjustable stop wing 29 is supported. A spring 30 coiled about the rod 28, has one end bearing against the oblique wall 20 and the other end 31 bears against the stop wing 29 and urges it in the 80 direction of the upper portion of the valve or damper 12. A chain or other flexible connection 32 is secured to the upper margins of the stop wing 29 and extends downwardly through an aperture in the bottom 85 of the casing 10. The lower end of the chain is provided with a hook 33 adapted to be engaged with any one of the series of down-turned hook shaped projections 34 carried by a wall plate 35 mounted on any suitable support 90 below the ventilator casing. By pulling down on the chain 32 and engaging the hook 33 with a desired plate hook 34, the stop wing 29 may be held at the desired inclination to limit the opening movement of the valve or 95 damper 12. The damper, stop wing, and their pivot rods are all supported from the pair of brackets 25 and in assembling the intake structure, they may be attached to the wall portion 20 either before or after 100 bending said wall portion upwardly from the bottom wall of the casing, and the side and top walls of the casing may then be assembled and secured to the side margins of 105 the bottom wall.

110

It will be understood that an opening 36 will be provided in the wall of the building to afford communication with the front end of the damper casing. The bottom of the casing will preferably be provided with a lining 37 of non-heat conducting material. The top wall will preferably have down-turned flanges 38 and 39 at its respective ends, whereby the entire air current will be directed toward the lower portion of the space enclosed by the casing.

When the stop wing is in the position in which it is illustrated by full lines in Figure 2, the valve or damper 12 will be held in the closed position, but by pulling downwardly on the chain 32 which passes through an opening in the floor of the casing, the stop wing may be swung toward or beyond its dotted line position as indicated in Figure 2, whereupon the major portion of the valve or damper 12 will swing inwardly under extremely slight excess pressure on its outer surface and will close the moment the direction of the air current is reversed. 25 When the direction of the wind is such as to allow it to blow directly through the intake, then, by releasing the chain 32, the stop wing will be raised by its spring to limit this opening movement of the valve 30 to any desired extent depending upon the temperature and velocity of the incoming air.

We claim:

1. A valve controlled ventilator intake member comprising an open ended casing adapted to fit between the floor joists of a building and having a bottom wall marginally up-turned and inwardly inclined at the inlet end portion of the casing, a set 35 of brackets secured to said up-turned wall portion, each provided at its respective ends with oppositely extending arms, and a pivot rod mounted in the apertures of the forwardly extending arms; a damper valve pivotally supported by said rod, another rod mounted in the apertures of the rearwardly extending arms and provided with an adjustable stop wing adapted to limit the opening movement of the damper valve; and 40 lining wall members having oblique faces adapted to form-seating for said damper valve in its closed position.

2. In a ventilator intake structure, the combination with an open ended casing having an upwardly and rearwardly inclined wall in the lower part of its front end por-

tion, a set of brackets secured to said wall each provided with forwardly and rearwardly extending arms, pivot rods mounted respectively in the forwardly and rearwardly extending arms, a balanced damper valve pivotally supported by the forward rod and an adjustable stop wing pivotally supported by the rearward rod, and means for adjusting the stop wing to various 60 positions for limiting the opening movement of said damper valve.

3. In a ventilator intake structure, the combination with an open ended casing having an upwardly and rearwardly inclined 70 wall in the lower part of its front end portion, a set of brackets secured to said wall each provided with forwardly and rearwardly extending arms, pivot rods mounted respectively in the forwardly and rearwardly extending arms, a balanced damper valve pivotally supported by the forward rod and an adjustable stop wing pivotally supported by the rearward rod, and means for adjusting the stop wing to various 75 positions for limiting the opening movement of said damper valve, said stop wing being provided with a spring tending to urge it in one direction and a manually operable member for urging it in the opposite direction. 80

4. In a valve controlled ventilator intake member, the combination with an open ended casing, of an obliquely disposed wall member crossing the lower portion of the casing, 85 brackets secured to said wall member and provided with forwardly and rearwardly projecting arms, pivot rods supported by the forwardly and rearwardly projecting arms respectively, a damper valve pivotally supported by one of said pivot rods, and a damper stop adjustably supported by the other pivot rod.

5. In a valve controlled ventilator intake member, the combination with an open ended casing having an interior transversely 100 extending bracketed support in its lower portion, transversely extending rods connected with the brackets of said support on opposite sides thereof, a damper valve pivotally supported by one of the rods, and an adjustable stop for the damper valve supported by the other rod, said transverse support, rods, valve and stop being adapted to be assembled as a unit preparatory to 105 assembly of the casing walls.
